CANAL LOCK

Leopold Rothmund, Stuttgart, Germany

Application April 23, 1935, Serial No. 17,760
In Germany May 12, 1934

3 Claims. (Cl. 61—8)

My invention relates to locks for ships to raise and lower them from a lower water level to a higher water level and vice versa respectively. More particularly, my invention relates to locks 5 of the type wherein two floating or diving troughs are provided in the lock basin or lock chamber. While one of these troughs is in its highest position, in which its inner space can be brought into communication with the upper water level, 10 the other trough occupies its lowest position, in which its inner space can be brought into communication with the lower water level. For the purpose of raising or lowering a ship, one of the two troughs is lifted by a lifting gear, while simultaneously therewith the other trough is lowered. 15 To enable these operations to be performed with a comparatively small consumption of power, the troughs are provided underneath their closed bottoms with an open-bottomed air-chamber, 20 which chambers contain air under pressure, the air-chamber of one trough being in communication with that of the other trough by an air-conduit. In this manner, the weights of the troughs resting on an air-cushion are balanced relative 25 to each other, and as the compressed air from the air-chamber of the descending trough is allowed to pass through said conduit to the air-chamber of the rising trough, it is evident that only a comparatively small consumption of power 30 is required for the lifting and the lowering of the two troughs.

Now, if the troughs are disposed, as has been done heretofore, in a lock basin connected with the lower water level, there result certain disadvantages. 35 For instance, the troughs will have a secure floating position only when in their lowest position.

Moreover, as is natural, the air pressure in such lower-level troughs is small, since the pressure level in the air-chamber is only by a slight safety degree lower than the ceiling of the air-chamber in the lower-level position of the trough. Furthermore, when such a lower-level trough ascends from its secure lower-level position to the 45 upper-level position, it reaches its relatively most unfavorable position both as regards its equilibrium and as regards its security from outside influences, due to changes in temperatures, wind pressure, shocks, etc. because the walls of the air-chamber of the trough are comparatively thin. This necessitates special safety measures, 50 whereby the simplicity of operation is of course affected. Of especial importance in this respect are the changes in the temperature of the air 55 affecting the compressed air in the air-chambers

of the troughs. The air-cushion in the air-chamber of the trough must always be equal to the height of the stage of the lock, and every variation in temperature must, therefore, be taken care of in that in case of a temperature increase air must be permitted to escape, whereas in case of a decrease in temperature additional compressed air must be supplied. Eventually, an auxiliary float must be provided to avoid the disadvantages due to temperature changes of the 10 compressed air in the air-chamber. 5

To further insure in lower-level troughs a uniform buoyancy, their walls must be given a certain inclination, which will be the more pronounced, the more the walls, for reasons of safety, have been artificially reinforced. The disadvantage resulting therefrom is that, except in the intermediate position of two cooperating troughs, the border faces between air-cushion and pressure level in the air-chambers, which 15 control the amount of the buoyancy, no longer correspond so that with equal speed of the two troughs, as is a requisite in the interest of the simplicity and security of the operation, the lifting gear must do considerable additional work. 20 25

These disadvantages are avoided by the present invention, according to which the floating troughs are disposed in a lock basin which is in communication with the upper water level, and according to which, moreover, the troughs and their air 30 chambers are so designed, that also in the upper level position of a trough its air chamber remains immersed in the water, stationary air conduits being provided for conducting air under pressure from the air chamber of one trough 35 to the air chamber of the other trough, the arrangement being such that the troughs can so far descend that their water level will be adjusted to the lower water level. The troughs, therefore, are upper water level troughs whereby, as 40 compared with lower water level troughs, the following advantages are secured. The air-chamber of an upper-level trough is always below water, and the trough has in the upper-level position a uniformly secure floating position. 45 Moreover, in the upper-level trough the pressure level, that is to say, the border-layer between the air-cushion and the water-level, must be disposed below the ceiling of the air-chamber about the amount of the depth of the immersion so 50 that the air-pressure is correspondingly higher necessitating greater strength of the walls of the air-chamber. An artificial reinforcement of the walls of the trough, therefore, can be dispensed with. Because of its strong walls and the fact 55

that the air-cushion commences about 3-4 meters below the level of the basin, an upper-level trough is superior to a lower-level trough. Moreover, the air-cushion in the air-chamber of an upper-level trough is only slightly affected by variations in temperature, so that these variations can be readily compensated for with a small compressor. Because the air-chamber of an upper-level trough is below water and always remains below water, involves the further advantage that having perpendicular walls, the trough has a uniform buoyancy in every position.

The air-chambers of two cooperating troughs may be in communication with each other by a stationary air-conduit located below the water level in the trough-basin, or they may also be connected with each other by an air-conduit suspended above said water-level.

In the latter case, the arrangement is such that the air-chambers are automatically engaged with the air conduit when rising and are automatically disengaged from the air-conduit when descending. In order to enable such an automatic engagement and disengagement, there are provided at the lower ends of the air-conduit as well as at the places in the air-chambers of the floating troughs to be connected with the air-conduit specially constructed parts which are concentrically arranged relative to each other so that the parts provided on the air-chambers of the troughs surround the corresponding parts provided at the lower ends of the air conduit, through which the compressed air pendulates between the air-chambers of two cooperating troughs.

My invention will now be further described with reference to the appended drawing, in which, by way of illustration, I have shown diagrammatically an embodiment of my invention and in which

Fig. 1 is a section through a lock-basin and two cooperating floating troughs therein provided with open-bottomed air-chambers and a stationary air-conduit below the level of the water; Fig. 2 is a sectional view showing two cooperating floating troughs and an air-conduit suspended above the water-level and arranged for automatic engagement with and disengagement from the air-chambers of the two troughs.

In Fig. 1, *a* denotes the lock basin. *b* and *b'* denote the two cooperating floating troughs. As shown, each trough is provided with an open-bottomed air-chamber *c* and *c'* respectively. At *d* is shown a stationary air-conduit, whereby the two air-chambers *c* and *c'* communicate with each other.

As shown in Fig. 1, the trough *b* is in its highest position, while the trough *b'* is in its lowest position. When the compressed air in the air-chamber *c* is conducted through conduit *d* to the air-chamber *c'*, the position of the two troughs will be reversed, that is to say, the trough *b* will descend to its lowest position, while the trough *b'* will ascend to its highest position. When the troughs occupy the highest position, the water level therein will be at the same height as the water level in the lock-basin. *g* denotes the height of the water-level in the trough *b'* when the latter occupies its lowest position.

As will, therefore, appear from Fig. 1, the proportion between the amount of the pressure in the air chambers and the weight of the troughs is so selected, that is to say, the height of the air chambers is so suited to that proportion, that in the elevated position of the troughs, as represented in Fig. 1 by the trough *b*, the pressure level lies below the ceiling of the air chamber the same

amount as the pressure level remains in the lowest position of the trough below the ceiling of the air chamber, which amount is made up of the floating height *H* and the safety margin *H'*.

According to Fig. 2, communication between the air-chambers of the two floating troughs is established by an air conduit suspended above the upper water level in the lock-basin. The two troughs and their corresponding air-chambers are designated by the same reference characters as in Fig. 1, that is to say, *b* denotes the trough occupying the upper level position and *b'* denotes the other trough shown in the position just prior to its descent, while *c* and *c'* respectively denote the corresponding open-bottomed air-chambers. Communication between the two air-chambers is established by the following means.

At *h* is indicated a supporting structure for an inverted U-shaped pipe *i*. The downwardly directed perpendicularly disposed portions *i'* and *i''* of tube *i* are made to a certain height with double walls forming an annular container closed at the bottom and open at the top. Over the perpendicular portions of pipe *i* is placed a movable pipe *j* open at the top and bottom and having its lower portion also made of double walls so that an annular container is formed closed at the top and open at the bottom. The inner wall of this annular container is made to engage at the top the annular container formed by *i'* and *i''*. The third element of the suspended air-conduit is a pipe *k* securely mounted on the top of air-chamber (*c*, *c'*). This pipe *k* is also made with double walls as shown, forming an annular container which is closed at the bottom and open at the top. The inner width of *k* is such that *k* and *j* can be readily telescoped relative to each other so as to form a closed conduit.

As will be evident from the drawing, a communication between the two air-chambers *c* and *c'* exists only during the descent and the ascent respectively of the two troughs. Shortly after the descending trough has commenced its immersing movement, the communication between the two air-chambers becomes automatically disconnected to be automatically re-established only when the immersed trough as it ascends reaches a position close to the upper water level. While the immersing trough descends, the other trough is at rest.

The air-tight seals between the three pipes or elements are effected by the above said annular or cylindrical containers being filled with water so that the compressed air is always shut off by a water column *z* to which corresponds the pressure of the compressed air in the air-chambers *c* and *c'*. There is always a water-seal between *i* and *j*, whereas the water-seal between *j* and *k* is automatically effected.

As compressed air is passed from the air-chamber *c* through the pipe *i* to the air-chamber *c'*, the position of the two troughs *b* and *b'* is reversed, that is to say, the trough *b* descends, while the trough *b'* ascends.

My invention is, of course, not limited to the disclosure as herein presented, since my invention is capable of various embodiments.

I claim:

1. In combination with a waterway having an upper water level portion including a lock basin having the same water level as said upper water level portion, a lower water level portion, and gates between said lock basin and said lower water level portion; a pair of floating troughs in said lock basin one to be elevated while the other is

lowered and vice-versa, said troughs having end gates, each trough also having as a fixed part thereof an open-bottom air chamber closed at its top and sides, and an air conduit connecting said air chambers, said air chambers being disposed relative to said troughs so as to be at all times completely submerged in the water of the lock basin.

2. The combination as set forth in claim 1 in which air under a predetermined pressure is present in the air conduit and in the air chambers, in which said air conduit is of U-shape and has a fixed position at all times completely below the level of the water in the lock basin and includes a pair of legs disposed, respectively, in the air chambers, and in which the tops of the legs of said conduit are disposed to remain above the level of the water in said air chambers in all operative positions of the troughs.
3. The combination as set forth in claim 1 in which the air conduit connecting the air chambers is of inverted U-shape and is fixed and includes a pair of legs one related to each trough,

and in which an air seal is provided between each leg and the air chamber of the related trough, each air seal comprising an open-top closed-bottom water chamber surrounding the lower portion of the conduit leg, an open-top closed-bottom water chamber carried by the trough in surrounding relationship to said first mentioned air chamber, a tube open at its ends and slidably mounted on the conduit leg in surrounding relationship thereto and having its lower end portion disposed in said first mentioned water chamber, a second tube carried by said first mentioned tube in surrounding relationship thereto and co-operating therewith to provide a third water chamber closed at its top and open at its bottom, the lower end portion of said second tube being disposed in said second mentioned water chamber, and water in said water chambers, the top edge of the inner wall of said second mentioned water chamber serving by abutment with the top wall of said third water chamber to effect lifting of said tubes when the trough is elevated.

LEOPOLD ROTHMUND.
